UNITED STATES PATENT OFFICE

2,284,084

GLOW DISCHARGE LAMP

Don Canady, Cleveland, Ohio

Application December 9, 1940, Serial No. 369,253

1 Claim. (Cl. 176—122)

My invention relates broadly to glow discharge lamps containing a gas or gases, and more particularly to a glow discharge lamp having a canal or channel arrangement incorporated therewith for circulating a cooling medium, such as water or air, therethrough to carry off some of the heat developed in the electrodes while in operation.

This improvement is designed to increase the life of the glow discharge lamp, to stabilize its operation, to increase the light output intensity, and to reduce the noise level in operation.

My invention will be described with reference to the drawing which accompanies and forms a part of the present specification, although it is to be understood that many modifications may be made in the glow discharge lamp and the arrangement of the cooling canal without departing from the principles of my invention.

Various modes for carrying the invention into effect are illustrated by way of example, in the accompanying drawing, in which—

Figure 1 is a sectional view of a glow discharge lamp illustrating and embodying the principles of my invention.

Figure 2 is a sectional view of another form of a glow discharge lamp, in which the cooling canal constitutes one of the electrodes, and positioned so that its longest dimension is horizontal to the vertical axis of the lamp or tube.

Figure 3 is an end view of another form of a glow discharge lamp.

Figure 4 is a section taken on line A—A in Figure 3.

Figure 5 is an end sectional view showing another modification wherein the constricted portion of the tube or lamp is divided so that the cooling medium may pass between them.

The glow discharge tube or lamp shown in Figure 1 comprises a bulb or envelope 10 having therein an inner envelope 11 in which the cathode 12 is mounted, insulated and sealed in any suitable practical manner. The cathode is made of suitable conductive material, preferably a metal, which preferably has a circular cross-section. The cathode may be surrounded by a tube 13 of insulating material to prevent the perimeter of the electrode from taking part in the discharge. The anode 14 is mounted upon the pinch by means of a supporting rod 15. The leading-in wires are shown at 16 and 17.

In the inner envelope 11 there is provided an integrally formed centrally disposed and upwardly extending wall 18 stopping short of the length of the envelope as at 19 to provide a passageway 20 between the chambers 21 and 22 so

5 that the cooling fluid may have an unrestricted flow therethrough. The structure just described constitutes a form of an upright U shaped tube. The legs may be bent as shown at 23 and 24. The flow of the cooling medium may be in the direction indicated by the arrows or conversely.

In the tube or lamp shown in Figure 2, the electrode 25 is a straight cylindrical metal tube, but may be rectangular or have any other suitable shape in cross-section without turn or curve. The tube duly functions as a conduit for the cooling fluid and also as an electrode. The ends 26 and 27 of the electrode may be covered or coated with any suitable insulating material, for instance magnesia, micanite or mica which is indicated at 28 and 29. The cooling fluid may flow through the electrode as indicated by the arrows or conversely. The electrode 25' is provided with an opening 25'', and is mounted on the pinch or press 25* by means of the supporting rod 25*. As a variant the electrode 25' may be an elongated rod-like electrode.

In the tube or lamp shown in Figure 3 and the sectional view of same in Figure 4, the tube is provided with a constricted passageway or capillary 31, and the electrodes 32 and 33 are in alignment. The width or diameter of the constricted passageway is less than the diameter of the tube proper and is centrally located as shown in Figure 3, so that the cooling liquid can pass around it in passing through the cooling chamber 34, 34'. The cooling liquid may enter at the inlet 35 and leave at the outlet 36, or conversely.

The tube is filled with a noble gas or a mixture of noble gases, and when a current is applied through the electrodes the gas becomes luminous. At the constricted portion of the tube where the current density is high, the light is much more intense, hence in this region considerable heat is created. By enclosing the constricted area within a water jacket, the heat is readily dissipated.

In Figure 5 the constricted portion of the tube is divided into two channels as at 37 and 38. The cooling liquid may enter the cooling chamber at the inlet 39 and leave by the outlet 40, or vice versa, and in doing so it passes through the passageway 41, provided between the constricted channels 37 and 38. This construction provides a light concentrating means to concentrate the glow in a neon tube like fashion upon portions of the bulb proper. The constricted portion or portions of the tube may be rectangular, cylindrical, or have any other shape in cross-section.

In accordance with the provisions of the patent statutes, I have described the principles of opera-

tion of my invention, together with the apparatus which I now consider to represent the best embodiments thereof, but I desire to have it understood that the apparatus shown and described is only illustrative, and that the invention may be carried out by other means.

What I claim as new and desire to secure by Letters Patent of the United States is:

In a glow-discharge lamp, the combination with a sealed vessel containing a gas charge, electrodes therefor, one of the said electrodes being a straight hollow cylindrical metallic mem-

ber having its longest dimension disposed transversely of the sealed vessel and having its ends extending beyond the sealed vessel, of a companion electrode having an opening therein and located beneath the straight hollow cylindrical metallic member and substantially parallel therewith and supported on the pinch by a supporting rod, the straight hollow cylindrical metallic member providing a path for a cooling fluid to pass therethrough.

DON CANADY.
